BOTTLE FILLER AND CAPPER MACHINE

Robert Francis Dorrell, Chicago, Ill., assignor of fifty per cent to William C. Dvorak, Chicago, Ill.

Application October 29, 1943, Serial No. 508,145

9 Claims. (Cl. 226—75)

The present invention relates to bottle filling and capping machines and more particularly to an hydraulically actuated bottle filling and capping machine.

The bottles to be filled travel in straight paths under the actuation of a novel and improved hydraulic actuating mechanism which eliminates the usual gearing and driving means which are present in the usual machine.

In the usual bottle filling and capping machine the bottles travel in curved paths under the actuation of motor driven gears and moving parts producing a machine which is characterized by its noise of operation resulting from the presence of a multiplicity of moving parts. In the bottle filling and capping machine constructed in accordance with the present invention the number of moving parts is reduced to a minimum and their elimination produces results in the machine which is quiet in its operation. The hydraulic system which produces the necessary travel of the bottles, both horizontal and vertical is simple and economically manufactured and is characterized by its freedom from breakdown and mechanical trouble.

It is an object of the present invention to provide a new and improved bottle filling and capping machine. Another object of the invention is to provide a new and novel hydraulically operated bottle filling and capping machine. A still further object of the invention is to provide a bottle filling and capping machine in which a central pressure creating means actuates a plurality of bottle filling and capping units simultaneously. A still further object of the invention is to provide an improved hydraulically actuated mechanism in a bottle filling and capping machine. These and other more specific objects will appear upon reading the following specification and claims and upon considering in connection therewith the attached drawings.

Turning now to the drawings in which a preferred embodiment of the invention is illustrated and in which the same reference character refers to the same parts in the various views;

Figure 1 is a front view of a machine constructed in accordance with the present invention, certain parts being shown in section;

Figure 2 is a vertical section through the machine at right angles to the showing of Figure 1;

Figure 3 is a diagrammatic view of the hydraulic and electrical circuits of the machine.

The machine may be divided broadly into two main parts, a bottle-actuating unit, indicated generally by the reference character 1, and a bot-

tle filling and capping head 2 positioned thereabove. The present invention resides in the first unit, the specific construction of the liquid feeding and of the bottle capping means not being a part of this invention, it being important only that they are capable of filling and capping a bottle which has been lifted into contact therewith. In the drawings the filling head is indicated by the reference character 3 while the capping head is indicated by the reference character 4.

The bottle moving unit 1 is housed within a casing 6 which is divided by a transverse wall 7 into a lower liquid-containing reservoir 8 and 15 into an upper mechanism-containing chamber 9. Upon the top surface of the casing 6 are positioned a plurality of elongated guides 11, each pair of guides defining a path for a line of bottles, as illustrated in Figures 1 and 2. Each path 20 passes under a pair of filling and capping heads 3 and 4 and at the end of each line there is provided a bottle pusher 12 the function of which is to urge the bottle line along its path between the guides in steps which are calibrated to advance the bottles one by one under the respective heads 3 and 4. It is to be noted that there are a plurality of pathways, and accordingly an actuating element 12 at the end of each path, the bottles being fed into the pathway in any suitable manner, or manually. At the opposite end 25 of the bottle travel there is provided a conveyor belt 13, clearly shown in Figure 2, and onto which the filled and capped bottles are pushed by the succeeding bottles to be carried away from the 30 machine.

As an empty bottles enters one of the bottle paths it moves in successive increments toward the filling head 3 and finally is advanced to a point immediately thereunder as is clearly illustrated by one of the bottles in Figure 2. When so positioned the bottle rests upon a resiliently supported lifting element, lifting cylinder or lifter 14 which is mounted for vertical displacement within a guideway 16. Each lifter system 40 includes a piston 17 slidably positioned within the cylinder 14 and which is actuated by a vertical rod 18 transmitting its force to the lifter proper 14 through a compressible coil spring 19 the presence of which provides a resilient mounting for the lifter.

The construction insures that the bottles are lifted gently and yet firmly into contact with the filling or capping head. As illustrated in Figure 2 a bottle which has been lifted into contact with the filling head 3 is subsequently advanced under

the capping head 4 to be lifted into contact with that head to be capped. The two lifters under heads 3 and 4 are adapted to work simultaneously and while one bottle is being filled the adjacent bottle, which has previously been filled, is being capped.

To actuate the bottle lifters 14 and the pusher 12 there is provided an hydraulic system which makes use of the liquid, which may be oil, contained in the reservoir 8 of the main casing 6. The rod 18 leading to each lifter 14 is connected to an hydraulically actuated piston 21 positioned within a cylinder 22. The latter is provided upon opposite sides of the piston 21 with ports 23 and 24 which are so positioned as not to be sealed off by the piston in its travel. Liquid forced into cylinder 22 below the piston 21 forces the piston upwardly and raises the bottle lifter. Liquid forced into the cylinder 22 above the piston forces it downwardly to lower the bottle lifter. To actuate the bottle pusher 12 that element is connected to a rod 26 which in turn is connected to a piston 27 within the hydraulic cylinder 28 having inlet ports 31 and 32 upon opposite sides of the piston. As in the case of the lifters the bottle pusher 12 is actuated by the hydraulically actuated piston depending upon its direction of movement which in turn is controlled by the entrance of fluid under pressure into the cylinder 28.

To control the flow of fluid into the cylinders and so to control the lifting operation and the pushing operation there is provided a fluid pump 36 driven by an electric motor 37, the current to which is controlled by a manually operable switch 38. The intake of pump 36 comprises a filter 39, to which it is connected by a pipe 41, located within the oil reservoir 8. Oil under pressure from the pump 36 passes via a pipe 42 through a check valve 43 on its way to a four way solenoid-operated valve 44. One exhaust port of valve 44 connects to a pipe 46 from which lead a plurality of pipes 47 each of which connects directly to a port 23 at the lower end of a bottle-lifting cylinder 22. To a second exhaust port of the valve 44 connects a fluid pipe or conduit 48 which connects to the upper inlet port 24 of each of the lifter-actuating cylinders 22, an intermediate pipe 49 being connected from each port directly to the pipe 48 in each case. As is clearly illustrated in Figure 3 the connections are identical for the lifters which lift the bottles into contact with the filling head and with the capping head.

With the valve 44 positioned to direct oil through the pipe 46 the pistons 21 are all forced upwardly and the lifters are moved vertically upward. With the valve 44 positioned to pass oil through the pipe 48 the pressure of the oil is upon the opposite side of the pistons 21 in the cylinders 22 and the lifters are moved downwardly to their lower positions.

It is desirable that the bottles be intermittently raised and lowered, and that during the period in which the bottles are lowered they be advanced in their travel. To accomplish this there is provided a sequence valve in one of the pipes 47 and one pipe 49. These sequence valves are indicated by the reference characters 51 and 52. With oil under pressure passing from the pump through the valve 44 and into the pipe 46 it passes via the pipe 47 into the lifter-actuating cylinder 22 resulting in the piston 21 being forced upwardly. When further movement of the piston is opposed as when the piston has reached the upper end of its travel, that is, the lifter 14 has forced a bottle tightly against the head 3, the pressure in-

creases, further piston movement is prevented, and the pressure within the pipe 47 and the valve 51 correspondingly increases. At a predetermined pressure valve 51 automatically changes its position and diverts the oil from the cylinder 22 into a pipe 53 which leads through a time delay valve 54 to the port 31 of the cylinder 28 housing the pusher-actuating piston 27. Time delay valve 54 has a characteristic which delays the passage of the fluid to the piston 28 for a sufficient period of time to enable the bottle positioned under the filling head to become filled. At the end of this time interval the valve 54 opens completely and fluid enters the cylinder 28 thereupon moving the piston 27 to the right, as viewed in Figure 3, and the pusher 12 into position to receive a new bottle. Had the valve 44 been positioned to direct oil through the pipe 48 a similar action would have occurred at the sequence valve 52 which would have redirected the oil from the intake port 24 of the cylinder 22 into a pipe 56 leading to the port 32 upon the opposite side of the piston 27. No time delay valve corresponding to valve 54 is present in the pipe 56 for when oil is passing through the valve 52 the lifter piston is being moved downwardly and when it reaches its final position there is no necessity for delay to enable the bottles to be filled and instead it is only desirable that the bottles be advanced. The hydraulic circuit is completed by drainage pipes 59 which lead from the various valves 51, 52, 54, 44 and from the pump 36 back to the reservoir 8. In the case of the first three valves mentioned these drainage pipes permit the oil to be forced from the cylinders when the pistons move in the reverse direction. In the case of valve 44 and the pump 36 the drainage pipes permit collected oil to return to the reservoir. A check valve 58 is provided between the valve 44 and the reservoir for safety purposes.

Clearly the valve 44 controls the operation of the various pistons. To control the valve and to effect the sequential operation of the machine the movable valve element is connected to a pair of solenoid armatures 61 and 62 having individual stator windings 63 and 64. The energization of winding 63 causes the armature 61 and the valve element to move in one direction while the energization of winding 64 effects movement of armature 62 and of the valve element in the opposite direction. The energization of winding 63 effects the movement of the valve element to the right as illustrated in Figure 3 to connect the pipe 48 with the pump 36 while energization of the winding 64 effects the movement of the valve element to the left, as viewed in Figure 3, and connects the pipe 46 with the pump.

To control the energization of the solenoid windings 63 and 64 there are provided a pair of switches 66 and 67 which are normally open but which are adapted to be held in closed position by a cam actuator 68 carried by the rod 26 which also actuates the bottle pusher 12. The source of incoming current indicated by the leads 71 and 72, and the switches 66 and 67 are connected in series, respectively, with their solenoid windings 62 and 63 across these incoming leads 71 and 72 by the conductors 73 and 74, respectively.

The operation of the construction, of the bottle filler and capper machine constructed in accordance with the present invention is as follows. The operator places the machine into operation by closing the manually operable switch 38 thereupon energizing the driving motor 37 which in turn actuates the hydraulic pump 36. Fluid, such

as oil, is drawn from the reservoir 8 and passes into the valve 44 which, it will be assumed, is initially so positioned that fluid passes through the pipe 46. Thereupon fluid under pressure will enter the individual cylinders 22 on the underside of the pistons 21 and those elements will be forced upwardly together with the bottle lifters connected thereto. The bottle below the filling head 3 will be moved upwardly into contact with that head and will be filled with liquid and the bottle in contact with the head 4 will be supplied with a cap.

After the piston 21 has reached the upper limit of its travel the liquid pressure will increase and the valve 51 will be actuated to direct fluid through pipe 53 to the time delay valve 54. This valve delays acting a suitable time to permit the bottle in contact with the head 3 to become filled and thereafter will direct the fluid under pressure into the valve chamber 28. As a result of this action piston 27 will move to the right, moving with it the bottle pusher 12 into a bottle receiving position and also moving the cam switch actuator 68 to the right to close the switch 67. Upon the switch 67 closing the winding 63 of the solenoid controlling the valve 44 is connected directly across the power leads 71 and 72 and the armature 61 is actuated moving to the right and effecting the closing of the pipe 46 and opening of the pipe 48 to the pressure-creating pump 36. Oil under pressure is directed through the pipe 48 and through the individual pipes 49 to the upper port of each of the cylinders 22 and the piston therein is forced downwardly thereby lowering the bottles from filling and capping heads 3 and 4. When the piston 21 actuating each lifter has reached the lower end of its stroke the pressure will build up within the upper part of the cylinder 22. When the pressure reaches a predetermined point the valve 52 will automatically change its internal relationship so that the oil is directed through the pipe 56 to the cylinder 28 through the port 32. Piston 27 will then be moved to the left as viewed in Figure 3 resulting in the advance of the bottles in the bottle path and of the movement of the switch actuator 68 finally into closing contact with the switch 66. Upon switch 66 being closed the winding 64 of the solenoid is energized and the valve movable element of valve 44 is moved to the left, as viewed in Figure 3, to its original position in which the fluid under pressure is again directed through the pipe 46. The lifting operation then again takes place.

I claim:

1. In a bottle filling and capping machine, a path for bottle travel, hydraulically actuated means to move a series of bottles along said path simultaneously and in a step-by-step progression, hydraulically actuated means to lift bottles in said series into operative relationship with filling and capping means positioned thereabove, a fluid pressure generating unit, valve means including pressure-operated valve means controlling the flow of fluid to said hydraulically actuated means to lift said bottles, a solenoid to position one of said valve means, electrical switch means positioned by the movement of said first-mentioned hydraulically actuated means to move a series of bottles and controlling the energization of said solenoid, and means to delay the movement of said last-mentioned means for a predetermined time interval after the lifting of said bottles to insure the filling of the bottle.

2. In a bottle filling and capping machine, a

path for bottle travel, hydraulically actuated moving means to move a series of bottles along said path simultaneously and in a step-by-step progression, hydraulically actuated lifting means to lift bottles in said series into operative relationship with filling and capping means positioned thereabove, a fluid pressure generating unit, valve means controlling the flow of fluid to said hydraulically actuated lifting means including a pressure operated valve to direct the fluid pressure on said hydraulically actuated moving means, a time delay valve to delay the effect of the action of said last mentioned valve on said hydraulically actuated moving means for a time interval sufficient to enable said bottle to be filled, and means to lower a lifted bottle.

3. In a bottle filling and capping machine, a path for bottle travel, hydraulically actuated moving means to move a series of bottles along said path simultaneously and in a step-by-step progression, hydraulically actuated lifting means to lift bottles in said series during periods of rest in said progression into operative relationship with filling and capping means positioned there-

above and including a resilient compressible bottle supporting element, a fluid pressure generating unit, fluid conduit means connecting said moving and lifting means to said unit, and a pressure operated valve in said conduit means normally directing the fluid to said lifting means but operable to direct said fluid from said lifting means under a predetermined pressure acting against the supporting element to lift the bottle into contact with said filling or capping means.

35 4. In a bottle filling and capping machine of the type having bottle moving and bottle lifting and lowering means, a path for bottle travel, hydraulically actuated moving means to move a series of bottles along said path simultaneously and in a step-by-step progression, fluid pressure generating means, fluid conduit means connecting said moving means to said generating means, fixed means to fill a bottle in said series, a vertically movable bottle lifting element positioned in said path below said fixed means to lift a bottle in said series of bottles during periods of rest in said progression, an hydraulic piston and cylinder unit to lift said bottle lifting element, conduit means connecting said unit to said fluid pressure generating means, means to direct fluid through said conduit means to actuate said piston to lift said element, and pressure actuated valve means to shunt said fluid past said unit in the presence of a predetermined fluid pressure effected by the resistance to movement of said piston.

50 5. The construction defined in the preceding claim characterized in that said bottle lifting element is vertically compressible and includes resilient means through which reactive force from said fixed means to fill a bottle is transmitted to said piston and to said fluid to actuate said pressure actuated valve means.

60 6. In a bottle filling and capping machine of the type having bottle moving, raising and lowering means, a bottle lifting element, bottle moving means to move a bottle to be filled on to said element, a first cylinder, a first fluid actuated piston in said cylinder connected to said element, first fluid conduit means connecting said cylinder to a source of fluid under pressure, a second cylinder, a second fluid actuated piston in said second cylinder connected to said bottle moving means to actuate same, and a second fluid con-

70

75

duit means connected to said second cylinder, and pressure operated valve means connected to said first and second fluid conduit means normally directing fluid to said first cylinder to actuate said first piston and said bottle lifting element but operable to direct the flow of fluid from said first cylinder through said second fluid conduit means to said second cylinder to actuate said second piston and said bottle moving means under a predetermined fluid pressure resulting from resistance to further movement of said first piston.

7. In a bottle filling and capping machine of the type having bottle moving, raising and lowering means, a bottle filling head, a compressible bottle lifting element positioned thereunder, bottle moving means to move a bottle to be filled onto said element, a first cylinder, a first fluid actuated piston in said cylinder, a source of fluid under pressure, first conduits connecting said first cylinder upon opposite sides of said piston to said source, valve means controlling the direction of fluid to said conduits, a second cylinder, a second fluid actuated piston in said second cylinder, second conduits connected to said second cylinder upon the opposite sides of said second piston, pressure controlled valve means connected to said first and second conduits controlled by the fluid pressure effective within said first cylinder to direct an actuating fluid pressure from said first cylinder to said second cylinder, and a delayed action valve in one of said second conduits to provide a time delay in the flow of fluid to said second cylinder after the pressure in said first cylinder on a lifting piston movement reaches the predetermined value to insure a sufficient time period for filling a lifted bottle, and means to alternate the flow of fluid from said source to said first conduits connected upon opposite sides of said first piston.

8. In a bottle filling and capping machine, a path for bottle travel, hydraulically actuated moving means to move a series of bottles along said path simultaneously and in a step-by-step progression, hydraulically actuated lifting means to lift bottles in said series during periods of rest in said progression into operative relationship with filling and capping means positioned thereabove and including a resilient compressible bottle supporting element, a fluid pressure generating unit, fluid conduit means connecting said moving and lifting means to said unit, a pres-

sure operated valve in said conduit means normally directing the fluid to said lifting means but operable to direct said fluid from said lifting means to said moving means under a predetermined pressure acting against the supporting element to lift the bottle into contact with said filling or capping means, second fluid conduit means connecting said moving and lifting means to said unit to convey a pressure to lower said lifting means, a second pressure operated valve in said second conduit means normally directing fluid to said lifting means to lower same but operable under a predetermined pressure opposing further downward movement of said lifting means to direct fluid from said lifting means to said moving means, characterized in that said moving means performs a working stroke under the pressure of fluid from said second fluid conduit means and withdraws to its position at the start of the working stroke under the pressure of fluid from said fluid conduit means, and means to alternate the flow of fluid to said fluid conduit means and to said second fluid conduit means from said fluid pressure generating unit.

9. In a bottle filling and capping machine of the type having bottle moving and bottle lifting and lowering means, a path for bottle travel, hydraulically actuated moving means to move a series of bottles along said path simultaneously and in a step-by-step progression, fixed means to fill a bottle in said series, a vertically movable bottle lifting element positioned below said fixed means, an hydraulic piston and cylinder unit to lift said bottle lifting element, conduit means connecting said unit to a source of fluid under pressure, means to direct fluid through said conduit means to actuate said piston to lift said element, pressure actuated valve means to shunt said fluid past said unit in the presence of a predetermined fluid pressure effected by the resistance to movement of said piston to said moving means to effect the movement thereof to a starting position, and means to direct fluid through said conduit means to actuate said piston to lower said element, and second pressure actuated valve means to shunt fluid past said unit in the presence of a predetermined pressure opposing further lowering of said element to said moving means to effect the movement thereof from said starting position.

ROBERT FRANCIS DORRELL.
